UNITED STATES PATENT OFFICE.

FRED BEYER, OF DENVER, COLORADO.

ARTIFICIAL FLOWER.

Application filed March 26, 1923, Serial No. 627,725. Renewed July 31, 1924.

To all whom it may concern:

Be it known that I, FRED BEYER, a citizen of the United States, residing at Denver, in the county of Denver and State of Colorado, have invented certain new and useful Improvements in Artificial Flowers, of which the following is a specification.

This invention relates more especially to the formation of artificial floral ornaments and it has for its primary object to produce a novel and attractive ornament from a pine cone.

The invention resides in a pine cone zinnia and the method of making the same as will be more fully described and claimed hereinafter, reference being made to the accompanying drawing wherein:

Figure 1, is a side elevation of a pine cone;
20 Figure 2, depicts the same after it has been topped;
Figure 3, is a perspective thereof following the removal of certain of its petals; and
25 Figure 4, is a view showing the same painted or decorated with colors.

Referring more in detail to the accompanying drawings, a pine cone 1 is topped, or has its upper portion removed along a transverse line so as to leave substantially two-thirds of the body of the cone remaining, as indicated at 2 in Figure 2. Following this, enough of the upper pine petals, indicated roughly at 3, are removed to leave a projecting core 4 which will constitute the center of the flower to be formed. These petals may be removed irregularly or roughly so that the remaining, projecting core will present a rough and natural appearance simulating the natural flower. The remaining petals extend radially from the center in substantially a flat or common plane. The artificial flower

thus formed is then decorated or colored as by being hand-painted, the tips 5 of the petals and the center 4 being preferably of a like shade while the main portions 6 of the petals are colored contrastingly to produce a pleasing and attractive appearance. The tips 5 of the petals are naturally of a 50 different shade of brown from the inner portions 6 of the petals and therefore define the different portions to be colored or painted. The coloring may be effected by hand painting, dipping or air brushing to produce the 55 gorgeous colors of the natural zinnia.

What is claimed is:—

1. An artificial flower comprising a cone body having certain of its petals removed to define the stamen portion of the flower. 60

2. An artificial, daisy-like flower comprising a fragmentary portion of a pine cone, and a roughened, raised central stamen portion defined by the removal of the upper petals. 65

3. The method of forming artificial flowers consisting in topping a pine cone, and roughly removing the upper petals from the remaining body portion to form the center of the flower. 70

4. The method of forming artificial flowers consisting in topping a pine cone, and roughly removing the upper petals from the remaining body portion to form the center of the flower and then coloring the exposed surfaces with contrasting colors. 75

5. The method of forming artificial flowers consisting in topping a pine cone, and roughly removing the upper petals from the remaining body portion to form the center of the flower, coloring the tips of the petals and the center in a like shade and the remaining surface of the petals in a contrasting shade. 80

In testimony whereof I affix my signature.
FRED BEYER.
